ELECTRIC LIGHTING FIXTURE SHIELD

Martin W. Schwartz and Max J. Marks,
Chicago, Ill.

Application September 20, 1947, Serial No. 141,528

Term of patent 14 years

(Cl. D48—23)

To all whom it may concern:

Be it known that we, Martin W. Schwartz and Max J. Marks, citizens of the United States and residents of Chicago, in the county of Cook and State of Illinois, have invented a new, original, and ornamental Design for an Electric Lighting Fixture Shield, of which the following is a specification, reference being had to the accompanying drawing, forming a part hereof.

In the drawing:

Figure 1 is a front elevational view of an electric lighting fixture shield partially broken away showing our new design;

Figure 2 is a side elevation of the fixture shield shown in Figure 1; and

Figure 3 is an end view of the shield shown in Figure 1.

We claim:

The ornamental design for an electric lighting fixture shield, as shown.

MARTIN W. SCHWARTZ.
MAX J. MARKS.
